UNITED STATES PATENT OFFICE.

FREEBORN F. RAYMOND, 2d, OF NEWTON, MASSACHUSETTS.

HEEL-NAILING MACHINE.

SPECIFICATION forming part of Letters Patent No. 271,118, dated January 23, 1883.
Application filed September 11, 1882. (No model.)

To all whom it may concern:

Be it known that I, FREEBORN F. RAYMOND, 2d, of Newton, in the county of Middlesex and State of Massachusetts, have invented a certain new and useful Improvement in Heel-Nailing Machines, of which the following is a full, clear and exact description, reference being had to the accompanying drawings, forming a part of this specification, in explaining its nature, in 10 which—

Figure 1 is a plan view of a templet-plate, templet-table, and nail-holder. Fig. 2 is a plan view of the same parts illustrating a modification. Fig. 3 is a vertical section upon the line 15 xx of Fig. 1, showing additionally the drivers and heel in position. Fig. 4 is a view representing another form of carrying out my invention with effect.

The invention relates especially to the nail-holder, and it is an improvement upon that described in Letters Patent Nos. 252,215 and 259,687, for heel-nailing machines, both granted to Henry A. Henderson, assignor. In said patents a perforated nail-holder having a perforated sliding plate or bottom for closing and opening the holes in the holder is shown and described, and I desire to do away with the use of the perforated sliding plate or bottom. To accomplish this I make the nail-holder A, 25 in two or more parts, a a' . These parts are adapted to be moved on the templet-plate, or a continuation thereof, upon a curved or straight line from the place where the nails are inserted into the nail-receiving holes of the nail-holder 30 to the point where they discharge the nails into the templet; and I have represented in Figs. 1 and 3 the parts a a' adapted to be moved upon their centers a^2 upon the templet B. Preferably each of these parts is provided 35 with the segmental gear a^3 at its end, which mesh with each other, so that the movement of one section of the nail-holder shall cause the movement of the other; and in use the nail-holder will have the position shown in 40 dotted lines in Fig. 1 in loading, and having been loaded, the operator, by means of the handle a^4 , moves both parts simultaneously to the position on the templet-plate shown in full lines, thereby causing the holes in the nail-holder to register with the holes in the templet and the nails to discharge.

Any suitable stop-lug or projection upon the templet-plate may be used for causing the movement of the parts to stop when the holes are brought into line with the templet-holes. 55 In lieu of this movement, I may use guiding-slots C, (shown in Fig. 2,) into which pins or projections c upon the under surface of the holders shall project. In this event the parts of the nail-holder would be moved from the 60 place where the nails were loaded to a position to cause the holes to register with the holes in the templet-plate upon a line or substantially upon a line with the guiding-slots. Of course, in lieu of the slots, there may be projections 65 upon the templet-plate for guiding the parts of the nail-holder into position, so that the holes therein shall register with the templet-holes, in which case the parts of the nail-holder may be loaded and moved on the templet- 70 plate until the guiding-projections are reached, when by these means they are brought into position over the templet to register. This construction is represented in Fig. 4. These guides may project into recesses in the nail-holder or bear upon the ends of each part. 75

It is obvious, on account of the location of the holes in the templet in relation to each other, that a nail-holder cannot be in one piece and be moved in one direction upon the templet, because of the liability of the holder unloading some of its nails into the wrong holes in the templet, as there are at least two holes which are likely to be upon the same line of movement, and of course the nail-holder would 80 discharge the nails into the first holes that registered. Therefore it is essential that it be divided in order that the movements shall be away from each hole, instead of upon a line with two or more of them; and while I have 85 shown the holder divided into two parts of course it may be divided into more, if desired, without departing from the spirit of the invention.

For ease and quickness of operation it is desirable that the movement of one part cause a like movement of the other; and while I have represented one way of obtaining this result I do not confine myself to that way, but include any mechanical equivalent for the mechanism shown and described.

It will be observed that this construction is

cheap, and that by it no auxiliary plate to cover and uncover the holes in the nail-holder is necessary.

Having thus fully described my invention, 5 I claim and desire to secure by Letters Patent of the United States—

1. In a heel-nailing machine, in combination with the templet and templet-plate, a nail-holder in two or more parts, which are adapted to 10 be moved upon the templet-plate and brought together into position to cause the holes of the nail-holder to register with the templet-holes, all substantially as and for the purposes described.

2. In combination with a templet, a sectional nail-holder and connecting mechanism whereby both sections are simultaneously moved forward, all substantially as and for the purposes described. 15

3. The combination of the templet-plate, the nail-holder in two or more parts, and suitable guides for centering the parts of the nail-holder upon the templet, all substantially as and for the purposes described. 20

F. F. RAYMOND, 2D.
